(57) **CLAIM**

The ornamental design for a display screen or portion thereof with graphical user interface, as shown and described.

DESCRIPTION

FIG. 1 is a front view of a first embodiment of a display screen or portion thereof with graphical user interface, showing my new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; and,

FIG. 6 is a front view of a sixth embodiment thereof.

The outer broken lines in FIGS. 1-6 depict a display screen or portion thereof and form no part of the claimed design. The remainder of the broken lines in the figures depict portions of the graphical user interface that form no part of the claimed design.

1 Claim, 6 Drawing Sheets
